BOW FACING OAR

Filed Oct. 18, 1929

UNITED STATES PATENT OFFICE

GEORGE F. WEBB, OF HAMILTON, ONTARIO, CANADA

BOW-FACING OAR

Application filed October 18, 1929, Serial No. 400,533, and in Canada December 13, 1928.

This invention relates to improvements in bow facing oars or rowing mechanism so arranged that the oarsman in rowing may be seated facing the bow of the craft, and consists of a sleeve-like member adapted to be detachably affixed to the gunwale of the craft, a tubular member adapted for a limited reciprocal rotary movement within the first member, but extending beyond the ends of that member, and an oar fulcrumed at one end of the tubular member, and a lever fulcrumed at the opposite end of that member, and a link pivotally connecting the inboard end of the oar with the outboard end of the lever.

One of the principal objects of the invention is to provide a rowing mechanism arranged in such manner that the oarsman may face the direction in which the craft is proceeding instead of necessarily facing astern as in the case of ordinary oars.

Another important object is to provide bow facing oars which may be adaptable to the usual oar-lock pin socket as are standard on most oar-propelled craft, and another is to provide a mechanism of the class specified which can be readily and compactly folded to be placed lengthwise within the craft when not in use as it is customary to do with ordinary oars, and which can be quickly removed from the gunwale and taken inboard in emergency such as when obstructions are met with or while in narrow waterways.

Another important object is to provide such a mechanism the parts of which can be easily disassembled and when disassembled will lie flat together for stowing, and still another is to provide in the construction for the elimination of any parts likely by their comparative minuteness to be mislaid during the stowing or taking down of the device, such as pins, bolts and the like, and especially there is provided a novel pivotal connection between the link and the oar and lever which by certain manipulation later to be described permits of easy separation of those parts yet affording no danger of accidental separation of the device when in use.

Still another object is to provide a device of the class specified which will be simple,

durable, efficient and inexpensive to manufacture.

These, together with other objects, may be attained by the construction, combination and arrangement of the parts as will be herein- 55 after more fully described, illustrated in the accompanying drawing, and ascertained in the claims hereunto annexed.

Referring to the drawing:

Figure 1 is a top view of a bow facing rowing device constructed in accordance with this invention; 60

Figure 2 is an enlarged, sectional outboard or side elevation taken on the line 2—2 in Figure 1, with, however, the parts in the remote background omitted to obviate confusion; 65

Figure 3 is a greatly enlarged, detailed top view of the sleeve-like member and the tubular member showing particularly the favoured method of detachably fulcruming the 70 oar and lever to the latter member;

Figure 4 is a still more greatly enlarged end or aft view of Figure 3;

Figure 5 is an enlarged, sectional end or aft view of the same taken on the line 5—5 in 75 Figure 2;

Figure 6 is an enlarged, detailed, top view of the aft end of the tubular member with the lever removed;

Figure 7 is a detailed end or aft view of 80 Figure 6;

Figure 8 is an enlarged, detailed elevation of the lever as viewed from aft; and,

Figure 9 is a greatly enlarged, detailed perspective view of the link and lever (or link 85 and oar) connection in process of being disconnected.

Similar reference characters refer to corresponding parts throughout the several views. 90

The sleeve-like member is indicated on the drawing by the numeral 10, and this member is provided with a permanently affixed pin 11. The pin 11 corresponds in use to the usual oar-lock pin provided with ordinary stern facing oars and is adapted to fit the usual oar-lock pin socket 12 in the gunwale G, and with which most oar-propelled craft are customarily provided, but that pin does not rotate with the motion of rowing as 100

does the usual oar-lock pin. The ends of the sleeve-like member 10 are provided with flanges 13 which extend below that member and embrace the gunwale 12, thus to keep that member in a relatively fixed position parallel to the gunwale, and these flanges are preferably formed by cutting the belly of that member first lengthwise from its ends to the width of the flanges to be formed, then upwardly, and finally straightening out the material thus cut to a relatively vertical position.

Adapted for a limited reciprocal rotary movement within the member 10 is the tubular member 14 the ends of which, however, project considerably beyond the ends of the sleeve member and those ends of the tubular member are formed into upper and lower ears 15. Centrally on the sleeve member 10 is a fixed pin 16 extending into the core of that member and engaging in an annular segmental slot 17 in the tubular member 14. This slot is of the proper length to limit the rotary movement of the tubular member 14 to the required rise and fall of an oar between the strokes of that oar. Furthermore the engagement of the pin 16 in the slot 17 prevents improper lengthwise movement of the tubular member.

30 The oar 18 is fulcrumed between the forward ears 15 and the lever 19 is likewise fulcrumed between the aft ears 15. While the upper of these ears, for simplicity in manufacture, may remain arcuate in cross-section in conformation to the tubular material from which they are formed, the lower of them are preferably filled to form even galleries 20 and it is upon these galleries that the oar 18 and the lever 19 are supported when in use. 35 This oar and lever carry pivot pins 21 provided with heads 22. Portions of these pins extend beneath the oar and the lever and enter sockets 23 in the lower ears, while the upper portions of the pins are embraced in diagonal notch slots 24 in the upper ears. 40 In setting up the mechanism it will be observed that if the oar and lever are first placed in an elevated position between the ears and in contact with the upper of those 45 ears rather than with the lower of them, those portions of the pins 21 extending beneath the oar, or lever, as the case may be, can be unobstructably carried between the ears whilst the upper portions of those pins 50 are traversing the diagonal notch slots 24, until the oar, or lever, as the case may be, arrives home, when the lower portions of those pins may drop into their sockets 23 and the oar, or lever, as the case may be, 55 comes to rest on its respective gallery. For locking the oar and lever in their fulcrumed position between the ears there are provided notched latches or keepers 25 on the upper ears. These latches are pivoted as at 26, and 60 are adapted to be swung in or out of engage- 65

ment with the pivots 21. Obviously the oar and lever may be disconnected from the tubular member by a reversal of the foregoing procedure.

Pivottally connecting the inboard end of the oar 18 and the outboard end of the lever 19 is the link 28. Although this link and its pivotal connections can be of any suitable form and produce the same ultimate result, it is found preferable to provide that link in the form of a rod provided with an eye 29 at one end and a hook 30 at the opposite end. The eye 29 is linked with a hook 31 on the outboard end of the lever 19 and the hook 30 is linked with an eye 32 on the inboard end of the oar 18. The relative position of these hooks and eyes is obviously immaterial, the foregoing relationship being illustrated by way of an example. Assuming, however, that that relationship is a preferable one, the end of the bill 33 of the loop forming the eye 29 is proportionately narrowed to a diameter approximately the intervening space or gap between the end of the bill 34 and the hook-back 35 of the hook 31, see Figure 9. Thus by manipulating the link 28 to a position where the hook bill 34 meets the narrowed end of the bill 33 on the eye, the hook and eye may be readily disengaged provided, of course, that the lever 95 has previously been disconnected from the ears 15 so as to free that lever for such manipulation. The linked connection between the link 28 and the oar 18 are similarly separable. Although it has been shown that the aforesaid connections are readily separable, obviously once the mechanism is locked in operative position it becomes impossible for those parts to become accidentally separated.

100 Those portions of the oar and lever which have been hitherto described are preferably of a metallic construction. The oar blade 36 and the major portion of its stem 37 however are preferably of the usual wooden construction and this stem may be united to the metallic portion by any suitable means. 105 Similarly a hand grip 38 of wood or other suitable material is united to the inboard end of the lever.

The metallic portions of the oar and lever are offset as at 39 and 40, respectively so that the ends of those members may be upon a common plane with the link 28, which latter rides back and forth atop the sleeve-like member during the course of the rowing strokes.

110 The hook 31 is preferably attached to the lever by enclosing the shank 41 of that hook in a loop 42 formed by rolling the end of the lever in that form, then providing a permanent union by any suitable means as by welding for example. Similarly the eye 32 is permanently secured to the oar. To provide for adjustment there are a plurality of holes 43 in the oar and in the lever, the pins 115

21 being interchangeable from one to the other of these holes.

In operation, considering the propelling stroke, the oarsman draws toward him the 5 inboard end of the lever in the same manner as he would an ordinary oar, the power being transmitted in a reverse manner to the oar by means of the link 28, thus directing the stroke of the oar in the same direction 10 as taken by the inboard end of the lever.

There has thus been provided a simple and efficient device of the kind described and for the purpose specified.

It is obvious that minor changes may be 15 made in the form and construction of the invention without departing from the material spirit thereof. It is not therefore desired to confine the invention to the exact form herein shown and described but it is 20 desired to include all such as properly come within the scope claimed.

Having thus described the invention, what is claimed as new, is:

1. In bow facing oars a mounting member adapted to be secured to a gunwale or other rigid part of a rowing craft, an oar fulcrumed to said member at one point, a lever fulcrumed to said member at another point remote from the first point, a link, 25 one member of a hook and eye combination on the inboard end of the oar, a complementary member of the hook and eye combination on the inboard end of the link, the width of the gap between the bill and back of the hook 30 being less than the diameter of the main portion of the eye but perceptibly greater than the diameter of a reduced minor portion thereof so that the hook and eye may be separable when the oar and link are in a certain inoperative relative position but inseparable when the oar and link are in operative position, said link having a hook and eye connection at its outboard end with the outboard end of the lever.

2. In bow facing oars a mounting member adapted to be secured to a gunwale or other rigid part of a rowing craft, an oar fulcrumed to said member at one point, a lever fulcrumed to said member at another point 50 remote from the first point, a link, one member of a hook and eye combination on the inboard end of the oar, a complementary member of the hook and eye combination on the inboard end of the link, the width of the gap 55 between the bill and back of the hook being less than the diameter of the main portion of the eye but perceptibly greater than the diameter of the reduced minor portion thereof so that the hook and eye may be separable when the oar and link are in a certain inoperative relative position but inseparable when the oar and link are in operative position, said link having a similar hook and eye connection at its outboard end with the outboard end of the lever.

3. In bow facing oars, a sleeve-like member adapted to be secured to a gunwale or other rigid part of a rowing craft and parallel with the gunwale, a tubular member having bearing within the sleeve-like member, a pair of ears formed on each end of the tubular member, and an oar fulcrumed between and to the forward pair of ears, a lever fulcrumed between and to the aft pair of ears, and a link pivotally connecting the inboard end of the oar with the outboard end of the lever.

4. In bow facing oars, a sleeve-like member adapted to be secured to a gunwale or other rigid part of a rowing craft and parallel with the gunwale, a tubular member having bearing within the sleeve-like member, a pair of ears formed on each end of the tubular member, an oar, a pivot pin carried by the oar and extending both beneath and above the same, the upper portion of said pin being adapted to enter a diagonal notch slot in the upper of the forward pair of ears, and the lower portion of said pin being adapted to enter a socket in the lower of those ears, a latch or keeper on the upper of the forward pair of ears adapted to swing about said pin to restrain the same from retreating out of said slot, a lever connected to the aft pair of ears in the same 95 specified manner as the oar is connected to the forward pair of ears, and a link pivotally connecting the inboard end of the oar with the outboard end of the lever.

5. In bow facing oars, a sleeve-like member adapted to be secured to a gunwale or other rigid part of a rowing craft and parallel with the gunwale, a tubular member having bearing within the sleeve-like member, a pair of ears formed on each end of the tubular member, an oar, a pivot pin carried by the oar and extending both beneath and above the same, the upper portion of said pin being adapted to enter a diagonal notch slot in the upper of the forward pair of ears, and the lower portion of said pin being adapted to enter a socket in the lower of these ears, a latch or keeper on the upper of the forward pair of ears adapted to swing about said pin to restrain the same from retreating out of said slot, a lever fulcrumed between and to the aft pair of ears, and a link pivotally connecting the inboard end of the oar with the outboard end of the lever.

6. In bow facing oars, a sleeve-like member adapted to be secured to a gunwale or other rigid part of a rowing craft and parallel with the gunwale, a tubular member having limited rotary reciprocal movement within said sleeve-like member and extending both forward and aft of the same, and an oar fulcrumed to the forward end of said tubular member, a lever fulcrumed to the aft end of said tubular member, a link pivotally connecting the inboard end of the 130

oar with the outboard end of the lever, means for limiting the reciprocal rotary movement of said tubular member, and means for preventing lengthwise movement of said tubular member.

- 5 7. In bow facing oars, a sleeve-like member adapted to be secured to a gunwale or other rigid part of a rowing craft and parallel with the gunwale, a tubular member
10 having limited rotary reciprocal movement within said sleeve-like member and extending both forward and aft of the same, and an oar fulcrumed to the forward end of said tubular member, a lever fulcrumed to the
15 aft end of said tubular member, a link pivotally connecting the inboard end of the oar with the outboard end of the lever, an annular segmental slot in said tubular member, a pin on the inner wall of the sleeve-like member
20 and extending into said slot whereby the reciprocal rotary movement of the tubular member is limited to the bounds of that slot and whereby lengthwise movement of said tubular member is prevented.
- 25 In testimony whereof he has affixed his signature.
